UNITED STATES PATENT OFFICE.

RUDOLPH SATTLER, OF CINCINNATI, OHIO.

PLATE-PRINTING MACHINE.

Application filed June 14, 1920. Serial No. 388,889.

To all whom it may concern:

Be it known that I, RUDOLPH SATTLER, a citizen of the United States, residing at Cincinnati, in the county of Hamilton and 5 State of Ohio, have invented certain new and useful Improvements in Plate-Printing Machines, of which the following is a specification.

My invention relates to printing, and 10 more especially to printing from engraved plates, and also is claimed broadly in my co-pending application, Serial No. 451,678, filed March 12, 1921. The object of my improvement is to provide simple mechanism 15 to utilize power operation, allowing a more compact design of the machine. Other objects will appear in the course of the ensuing description.

I attain these objects by the device illustrated, for example, in the accompanying drawings, in which—

Figure 1 is a general perspective view of a machine embodying my invention, together with a preferred support therefor;

Fig. 2 is a side elevation of the machine, with the support omitted;

Fig. 3 is a conventional vertical cross-section on planes corresponding to the broken line 3—3 of Fig. 2; and

Fig. 4 is a vertical lengthwise section on a plane corresponding to the line 4—4 of Fig. 3.

The frame of the machine comprises a base 1, upstanding sides 2 and 3, and a top 4 on the tops of the sides 2 and 3, across over the base 1. The traveling bed 5 is mounted over the top 4, between the standards 6 that extend up from opposite sides of the top 4 about midway of the length of the machine; this bed 5 resting on rollers journaled in the top 4, as will be described, so that this bed can travel or reciprocate lengthwise of the machine. As shown in the drawings, the front end of the machine, 45 where the operator stands, is at the right; and the bed 5 is shown as being at its forwardmost position, at the right. It then rests on two rollers 7 journaled near opposite sides of the top 4, and on the middle pressure roller 8 which is journaled in the top 4 below the standards 6. Near the left-hand or rear end of the top 4 are two other rollers 9, like the rollers 7, near opposite sides of the top 4. These positions of the 50 rollers 7 and 9 will be understood from

Fig. 3, where the rollers 9 are shown by dotted lines, in front-to-rear alinement with the end parts of the larger middle roller 8, there shown in section. The bed 5 has heavy sides 10 with their bottoms faced to 60 bear on the finished peripheries of the rollers 7, 8 and 9; the rear end of the bed coming onto the rear rollers 9 before the front end leaves the front rollers 7, and the bed always bearing on the middle pressure 65 roller 8. Between these sides 10 the bed is thinner, except along its middle, for a considerable distance from its front end, where it has a middle bearing rib 11 of ample thickness, with its bottom faced to bear on 70 the middle part of the middle pressure roller 8 as the bed travels backward.

Each standard 6 is open and forms a guideway for a respective bearing-block 12 to slide up and down therein, supported by 75 a spring 13 between its bottom and the bottom of the guideway, and held down by an adjusting screw 14 passing down through a cap 15 fixed on top of the standard. These blocks, with their springs 13 and screws 14 80 at the opposite sides of the machine, support the D-roller 16, of half-cylindrical shape, to rotate over the bed 5, having the transverse shaft 17 through it and extending into the blocks 12, and having at the 85 left side of the machine (looking from the front) a hub 18 against the respective block 12. At the opposite side, a cam 19 and a spur gear 20 are fixed on the shaft 17 between the D-roller 16 and the respective 90 block 12; the cam 19 being next to the D-roller.

The pressure roller 8, before described, has a shaft similarly supporting it in its bearings in the top 4, and is extended to 95 the left against its bearing; but at the other side, fixed to this shaft along with the pressure roller 8, are a gear 21 next to the roller 8, and another spur gear 22 between this gear 21 and the shaft bearing and in 100 mesh with the spur gear 20 of the D-roller 16. A rack 23 is fixed on the right-hand side of the bed 5, extending from near its front end near to the gear 21, but out of reach thereof when the bed 5 is at its forwardmost position as shown in the drawings. This gear 21 is a spur gear, but has its teeth omitted throughout a considerable segment, as seen at 24, at the top of the gear as shown in the drawings.

The cam 19, turning with the D-roller, has a recess 25 in its periphery, occupying the rear lower quarter of the rotation circle of the cam when the bed 5 is farthest forward, as the drawings show. A pedestal 26 fixed on the right-hand side of the bed back of the standard 6 and cam 19, has a bar 27 mounted in it for forward and rearward adjustment by means of a suitable adjusting screw 28; this bar having a properly shaped nose 29 that extends very close to the recessed part of the cam periphery when the parts are in the described positions. This periphery is properly concave 15 within this recess.

The bed 5 is held down on its supporting rollers 7, 8 and 9 by a clip 30 attached to the top 4 and extending over the right-hand edge of the bed. Stoppage of the bed 5 is effected at the forward end of its reciprocation by a suitable cushioning device 31 fixed to the top 4 and engaging the screw 32 on the right-hand side of the bed. Return of the bed toward the front of the machine is caused by a flat spring 33 (Fig. 3) coiled around a transverse shaft 34 that is fixed in the top 4 to the rear of the pressure roller 8; this spring 33 having its inner end fixed to this shaft and its outer end 25 fixed to the inner wall of a drum 35 rotatably mounted on the shaft 34 around the spring, and a flat flexible band 36 being fixed to the rear end of the bed 5 by one of its ends and having its other end fixed 30 to the drum periphery, around which it winds as the spring 33 rotates the drum toward the front of the machine, pulling the bed 5 in that direction, and from which it unwinds as the bed is driven to the rear, 35 against the force of the spring.

The gear 22 that meshes with the D-roller gear 20 also meshes with a spur gear 37 fixed on a transverse shaft 38 journaled in the frame sides 2 and 3. At the opposite 45 side of the machine a spur gear 39 is loosely mounted on this shaft 38, as is also a clutch-member 40, this member and the hub of the gear 39 having suitable friction-disks 41 between them, and being held tightly together by a nut 42 screwed on a sleeve 43 which the clutch-member 40 has extending through the gear hub. Another clutch-member 44, at the right, is fixed on the shaft 38, and has a clutch-bar 45 mounted in it to 50 slide toward the adjacent face of the member 40, which face has clutch-teeth 46 for the bar 45 to engage with as the gear 39 turns over toward the front of the machine and as the bar is slid toward it by a small 55 compression spring 47 at the right-hand end of the bar 45 (Fig. 2.) This bar 45 is recessed to receive a small lock-block 48, pressed to the left by another small spring 49 compressed between it and the right-hand 60 end of the bar recess.

The operating lever 50 is fulcrumed in the left side of the top 4 and extends forwardly within convenient reach of the operator. Its fulcrum shaft extends inside the top and has fixed on it the clutch-controlling arm 51, extending down behind the clutch for its lower end to enter an annular recess between the clutch-members 40 and 44 and reach the clutch-bar 45, sliding across this recess. This end of the arm 51 is beveled to a rather sharp edge; and the left side of the arm has a groove 52. The clutch-releasing arm 53 is also fixed on the operating-lever fulcrum-shaft and extends down in front of a cam 54 fixed on the shaft 38 70 along with the clutch-member 44 with its periphery having an abrupt drop 55 and increasing in radius from the inner end of this drop around to the outer end thereof. Depression of the operating-lever 50 thus 75 swings the controlling-arm 51 away from the clutch, and swings the releasing arm toward the cam 54.

The spur gear 39 meshes with a pinion 56 fixed on a transverse shaft 57 along with 80 a spur gear 58 near the opposite or right-hand side of the machine; this shaft 57 being journaled in the frame sides 2 and 3. An electric motor 59 is mounted on the base 1 of the machine, between the frame sides, and 85 has a pinion 60 meshing with this other gear 58. A safety-pawl 61 is pressed forward against a pin 62 in the left end of the D-roller 16, by a spring 63.

A bracket 64 is mounted in a suitable vertical guideway 64' extending down from the front end part of the frame top 4; this bracket 64 extending inside the frame and having side clips 64''. It is clamped at any suitable height on the guideway 64' by 100 a thumb-clamp 64^a, to hold a suitable heater, such as the alcohol lamp 64^b (Fig. 1) at a proper distance below the bed 5, as is required in machines of this character, to maintain a proper consistency of the ink 105 on the engraved plate.

The D-roller 16 has recesses along the ends of its semi-circular periphery, across the machine, occupied by clamp-bars 65 which are hung on small links 66 pivoted 110 to the ends of the roller 16 so that these bars 65 may be swung out of their recesses or thereinto; the links 66 having fingers 67 past the bars 65, and flat springs 68 being fixed to the flat sides of the D-roller 16, 115 with bends forming shoulders near the free ends of the springs, to snap over the fingers 67 as the bars swing into the recesses. These parts are preferably so arranged that the recesses are cut in from the cylindrical surface of the roller substantially on the roller diameter; the roller being sufficiently greater than a half-cylinder to accommodate the parts as described. Also, the sides, or 120 corners, of the roller are recessed to receive 125 the parts as described. Also, the sides, or 130 corners, of the roller are recessed to receive

the links 66 (Fig. 2) so that the entire D-roller construction is very compact when the clamping devices are closed.

I prefer to mount the machine on a suitable support, preferably the cabinet 69 (Fig. 1) with a low part 70 on which the machine is firmly supported, and a higher part 71 having a flat top at about the height of the top surface of the traveling bed 5, thus forming a work-table very close to the right-hand side of the machine, and having a leaf 72 at the left, both of these being possible in absence of the cumbersome hand-operating device on all hand-operated plate printing-machines, at one side. The drawers 73 of the cabinet afford space for storage of plates, tools, supplies and the like, with very convenient access of the operator.

Operation: Suitable backing is clamped around the D-roller 16 by means of the clamp-bars 65. The engraved plate A is laid on the bed 5, inked, and the stock B laid on the plate A without any positive stop to gauge the position of the paper stock B on the plate A; this being effected merely by drawing a line on the plate A to mark where an edge of the stock B is to be placed. It is for this reason that the rack 23 is not allowed to mesh with the gear 21 until it has traveled rearwardly some distance; and the cam 19 on the D-roller and the nosed bar 27 are provided to cause the initial travel of the bed 5 by their coaction.

Thus, with the bed 5 at its forward position as shown in the drawings, and the plate A and work B thereon as just described, the operating-lever 50 is depressed, withdrawing the controlling-arm 51 from the clutch recess and allowing the clutch-bar 45 to be pressed by its spring 47 over against the face of the clutch-member 40, which is rotated forwardly by the motor 59 through the medium of the gear train. This depression and withdrawal is permitted because the least radius of the cam 54 is opposite the lower end of the releasing-arm 53; and the parts are held in this position before the clutch-bar is pushed over, by the left end of the clutch-bar recess entering the groove 52 of the controlling-arm 51.

When the clutch-bar 45 is engaged by a clutch-tooth 46, the D-roller is rotated over forwardly and downwardly toward the bed 5, through the medium of the gears 37, 22 and 20; and the concave recessed part of the cam 19 begins to engage the nose 29 of the bar 27, starting the bed backwardly very slowly and gently, thus avoiding jarring of the stock B from its correct position on the plate A. Further turning of the cam with the D-roller advances the bed at an increasing rate, until, when the first tooth of the gear 21, at the front of its vacant space 24, engages with the oncoming rack tooth, these parts are traveling at substantially the same

speed. Then the travel of the bed 5 is constant, as driven by the gear 21 meshing with the rack 23 in an ordinary manner, until the vacant space 24 comes around to the rack. After this occurs, the cam 54, pressing the releasing arm 53 forwardly and drawing the controlling-arm 51 into the clutch recess, has carried this operation far enough for the small left-hand spring 49 to overcome the right-hand spring 47 in the clutch, under pressure of the lock-block 48 pressed to the right by the incoming beveled end of the arm 51. This withdraws the clutch-bar 45 from the clutch-tooth 46, and the part of the bar 45 at the left end of its recess enters the groove 52 of the arm 51, as before, stopping the rotation of the shaft 38, gears 37, 22, 20, D-roller 16, and also of the bed-driving gear 21, all of which have made exactly one revolution, so that all of their parts are in the initial position.

During this travel of the bed 5, the D-roller, pressed down by its adjusting screws 14 with the correct pressure, has received the work B and plate A between it and the bed, making the impression on the lower surface of the work, according to the engraving on the upper surface of the plate; and this D-roller has continued backwardly and upwardly from the bed, to its initial position, as just described. When it reaches this position, the safety pawl 61 receives the D-roller side pin 62, against which it was pressed by its spring 63 as the D-roller passed through this part of its revolution, holding the D-roller securely in its position ready for the next impression, without danger to the operator's hands.

As the last tooth of the gear 21 leaves the rack 23, the bed, thus released from the backward-driving action, is quickly returned forwardly by the action of the spring 33, which became coiled more tightly as the bed, in its rearward travel, unwound the band 36 from the drum 35; this spring now uncoiling and rewinding the band 36 onto the drum 35 and thereby pulling the bed forwardly with the rear end of this band. As the spring 33 uncoils, it weakens in its pulling action, so that the final stage of the forward return of the bed is relatively slow, and the bed is thus very readily stopped at its forward position by the cushion-stop 31. The machine is then ready for the next impression; and will perform a complete operation as described, at each depression of the operating-lever 50 while the motor 59 is running.

Modifications may occur in adapting the invention to various uses, or under different conditions, or as matters of preference, and therefore, while certain constructional details are deemed preferable in connection with my invention, and I have shown and described these rather specifically in eluci-

dating the construction and use of my invention, as is required, I do not wish to be understood as being limited to such precise showing and description, but having thus 5 fully described my invention, what I claim as new and desire to secure by Letters Patent is:

1. In a machine of the character described, a traveling bed adapted to carry a printing 10 plate with stock held in correct printing position on said plate merely by the friction between the stock and the plate, pressing means having a surface with a movement to press said stock against said plate during 15 part of the travel of said bed, and mechanism to cause said movement of said pressing surface, and to cause said travel of said bed positively concurrently with said movement of said surface during the pressure of said 20 pressing means on said stock, comprising a cam acting on said bed whereby said travel is initiated at a speed gradually increasing up to the speed of said pressing-surface movement.
2. In a machine of the character described, a traveling bed to carry a printing plate with stock thereon, pressing means to press said stock on said plate at each travel of said bed, mechanism having a positive operation to cause travel of said bed and then release said bed for return from said travel, a spring operatively related to said bed whereby it has an increasing tendency to return said bed from said travel as said 35 travel progresses, and whereby said spring returns said bed from said travel when said bed is released by said mechanism, and elastic cushioning means to stop the return motion of said bed.
3. In a machine of the character described, a rectilinearly reciprocating bed to carry a printing plate with stock thereon, segmental rotary pressing means to press said stock thereon during reciprocation of said bed in one direction and to withdraw from said bed during reciprocation thereof in return direction, a pressure roller supporting said bed against the pressure of said pressing means, and mechanism to positively rotate said pressing means and said pressure roller and to reciprocate said bed in said one direction, and to release said bed for return reciprocation thereof.
4. In a machine of the character described, a rectilinearly reciprocating bed to carry a printing plate with stock thereon, segmental rotary pressing means to press said stock thereon during reciprocation of said bed in one direction, a rack secured to 50 said bed substantially parallel with said reciprocation, a gear having teeth omitted throughout a part of its circumference, to mesh with said rack for reciprocation of said bed in said one direction, and to un-

mesh therefrom and permit return reciprocation of said bed, a second gear coaxially fixed to this gear, a gear coaxially fixed to said pressing means and meshing continuously with said second gear, whereby said pressing means is rotated toward said bed 65 during said reciprocation in said one direction and withdrawn from said bed during said return reciprocation, and means having an operation to rotate said gears.

5. In a machine of the character described, a rectilinearly reciprocating bed to carry a printing plate with stock thereon, segmental rotary pressing means to press said stock thereon during reciprocation of said bed in one direction, a rack secured to 70 said bed substantially parallel with said reciprocation, a gear having teeth omitted throughout a part of its circumference, to mesh with said rack for reciprocation of said bed in said one direction, and to unmesh therefrom and permit return reciprocation of said bed, a second gear coaxially fixed to this gear, a gear coaxially fixed to said pressing means and meshing continuously with said second gear, whereby said 75 pressing means is rotated toward said bed during said reciprocation in said one direction and withdrawn from said bed during said return reciprocation, and means having an operation to rotate said gears.

6. In a machine of the character described, a rectilinearly reciprocating bed to carry a printing plate with stock thereon, segmental rotary pressing means to press said stock thereon during reciprocation of said bed in one direction, a rack secured to 80 said bed substantially parallel with said reciprocation, a gear having teeth omitted throughout a part of its circumference, to mesh with said rack for reciprocation of said bed in said one direction, and to unmesh therefrom and permit return reciprocation of said bed, a second gear coaxially fixed to this gear, a gear coaxially fixed to said pressing means and meshing continuously with said second gear, whereby said 85 pressing means is rotated toward said bed during said reciprocation in said one direction and withdrawn from said bed during said return reciprocation, and means having an operation to rotate said gears.

7. In a machine of the character described, a rectilinearly reciprocating bed to carry a printing plate with stock thereon, segmental rotary pressing means to press said stock thereon during reciprocation of said bed in one direction, a rack secured to 90 said bed substantially parallel with said reciprocation, a gear having teeth omitted throughout a part of its circumference, to mesh with said rack for reciprocation of said bed in said one direction, and to unmesh therefrom and permit return reciprocation of said bed, a second gear coaxially fixed to this gear, a gear coaxially fixed to said pressing means and meshing continuously with said second gear, whereby said 95 pressing means is rotated toward said bed during said reciprocation in said one direction and withdrawn from said bed during said return reciprocation, and means having an operation to rotate said gears.

8. In a machine of the character described, a rectilinearly reciprocating bed to carry a printing plate with stock thereon, segmental rotary pressing means to press said stock thereon during reciprocation of said bed in one direction, a rack secured to 100 said bed substantially parallel with said reciprocation, a gear having teeth omitted throughout a part of its circumference, to mesh with said rack for reciprocation of said bed in said one direction, and to unmesh therefrom and permit return reciprocation of said bed, a second gear coaxially fixed to this gear, a gear coaxially fixed to said pressing means and meshing continuously with said second gear, whereby said 105 pressing means is rotated toward said bed during said reciprocation in said one direction and withdrawn from said bed during said return reciprocation, and means having an operation to rotate said gears.

9. In a machine of the character described, a rectilinearly reciprocating bed to carry a printing plate with stock thereon, segmental rotary pressing means to press said stock thereon during reciprocation of said bed in one direction, a rack secured to 110 said bed substantially parallel with said reciprocation, a gear having teeth omitted throughout a part of its circumference, to mesh with said rack for reciprocation of said bed in said one direction, and to unmesh therefrom and permit return reciprocation of said bed, a second gear coaxially fixed to this gear, a gear coaxially fixed to said pressing means and meshing continuously with said second gear, whereby said 115 pressing means is rotated toward said bed during said reciprocation in said one direction and withdrawn from said bed during said return reciprocation, and means having an operation to rotate said gears.

10. In a machine of the character described, a rectilinearly reciprocating bed to carry a printing plate with stock thereon, segmental rotary pressing means to press said stock thereon during reciprocation of said bed in one direction, a rack secured to 120 said bed substantially parallel with said reciprocation, a gear having teeth omitted throughout a part of its circumference, to mesh with said rack for reciprocation of said bed in said one direction, and to unmesh therefrom and permit return reciprocation of said bed, a second gear coaxially fixed to this gear, a gear coaxially fixed to said pressing means and meshing continuously with said second gear, whereby said 125 pressing means is rotated toward said bed during said reciprocation in said one direction and withdrawn from said bed during said return reciprocation, and means having an operation to rotate said gears, and a clutch manually actuated to cause said operation

and automatically actuated to end said operation after a single unmeshing of said gear from said rack.

7. In a machine of the character described, a rectilinearly reciprocating bed to carry a printing plate with stock thereon, segmental rotary pressing means to press said stock thereon during reciprocation of said bed in one direction, a rack secured to 10 said bed substantially parallel with said reciprocation, a gear having teeth omitted throughout part of its circumference, to mesh with said rack for reciprocation of said bed in said one direction, and to unmesh therefrom and permit return reciprocation of said bed, a second gear coaxially fixed to this gear, a gear coaxially fixed to 15 said pressing means and meshing continuously with said second gear, whereby said 20 pressing means is rotated toward said bed during said reciprocation in said one direction and withdrawn from said bed during return reciprocation, said bed carrying its rack out of reach of said gear upon 25 said return reciprocation, a cam fixed to said pressing means, having a peripheral concavity, engaging means on said bed, said cam being so positioned that it receives said 30 engaging means in said concavity when said bed returns, whereby engagement of the surface of said concavity with said engaging means initiates the next reciprocation of said bed at a gradually increasing speed until said rack again meshes with said gear, 35 means having an operation to rotate said gears, and a clutch manually actuated to cause said operation and automatically actuated to end said operation after a single unmeshing of said gear from said rack.
- 40 8. In a machine of the character described, a frame, a rectilinearly reciprocating bed on said frame, to carry a printing plate with stock thereon, standards extending up from said frame at opposite sides 45 of said bed, segmental pressing means journaled transversely in said standards to press said stock on said plate during reciprocation of said bed in one direction, and mechanism to reciprocate said bed and rotate said 50 pressing means, located within the lateral limits of said frame.

9. In a machine of the character described, a frame, a rectilinearly reciprocating bed on said frame, to carry a printing 55 plate with stock thereon, standards extending up from said frame at opposite sides of said bed, segmental pressing means journaled transversely in said standards to press said stock on said plate during reciprocation of said bed in one direction, and mechanism having an operation to reciprocate said bed and rotate said pressing means, located within the lateral limits of said frame and comprising a clutch below said

reciprocating bed, manually actuated to 65 cause said operation and automatically actuated to end said operation after a single complete reciprocation of said bed.

10. In a machine of the character described, a frame, a rectilinearly reciprocating bed on said frame, to carry a printing plate with stock thereon, standards extending up from said frame at opposite sides of said bed, segmental pressing means journaled transversely in said standards to press 70 said stock on said plate during reciprocation of said bed in one direction, a rack secured to said bed substantially parallel with the line of reciprocation thereof, a gear journaled transversely in said frame and 75 having teeth omitted throughout a part of its circumference, to mesh with said rack for reciprocation of said bed in said one direction, and to unmesh therefrom and permit return reciprocation of said bed, a second gear coaxially fixed to this gear, a gear 80 coaxially fixed to said pressing means and meshing continuously with said second gear, whereby said pressing means is rotated toward said bed during said reciprocation in 85 said one direction and withdrawn from said bed during said return reciprocation, a clutch-shaft journaled transversely in said frame below said reciprocating bed, a gear coaxially fixed on said clutch-shaft and 90 meshing with said second gear, a clutch-gear rotatable concentrically with but loose from said clutch-shaft, a clutch comprising 95 means for manually engaging said clutch-gear with said clutch-shaft and means for 100 automatically disengaging said clutch-gear from said shaft after a single unmeshing of said gear from said rack, and motive means operatively related to said clutch-gear.

11. In a machine of the character described, a traveling bed, rotary means to coact with the bed, means to rotate said rotary means, means to cause travel of said bed while said rotary means coacts with said bed, a cam rotated with said rotary means, having a concavity in its periphery, and engaging means on said bed, entering said concavity for engagement to move said bed at a speed gradually increasing up to the speed of said rotary means, prior to the co-action of said rotary means with said bed.

12. In a machine of the character described, a traveling bed, rotary means to coact with the bed, means to rotate said rotary means, means to cause travel of said bed while said rotary means coacts with said bed, a cam rotated with said rotary means, having a concavity in its periphery, engaging means on said bed, entering said concavity for engagement to move said bed 120 at a speed gradually increasing up to the speed of said rotary means, prior to the co-action of said rotary means with said bed,

all parts of said cam being confined within the circle of coaction of said rotary means with said bed.

13. In a machine of the character described, a frame, a bed rectilinearly reciprocatable on said frame, pressing means on said frame above said bed, mechanism for reciprocating said bed and operating said

pressing means, confined within the lateral limits of said frame, and a support for said frame comprising a low part under said frame and a higher part with a flat top substantially in the horizontal plane of the upper surface of said bed, extending close to one side of said frame.

RUDOLPH SATTLER.
